UNITED STATES PATENT OFFICE.

MURRAY BACON, OF PHILADELPHIA, PENNSYLVANIA, ASSIGNOR TO THE NOVELTY ELECTRIC COMPANY, OF SAME PLACE.

DESIGN FOR A FRAME FOR TELEGRAPH-INSTRUMENTS.

SPECIFICATION forming part of Design No. 16,803, dated July 20, 1886.

Application filed March 20, 1886. Serial No. 196,034. Term of patent 7 years.

To all whom it may concern:

Be it known that I, MURRAY BACON, of Philadelphia, in the county of Philadelphia and State of Pennsylvania, have invented and

5 produced a new and original Design for a Frame for a Telegraph-Instrument, of which the following is a specification, reference being had to the accompanying drawings, forming a part thereof, wherein—

10 Figure 1 illustrates my design for a frame for a telegraph-instrument in perspective view. Fig. 2 is a side view of the anvil-base and upright or post. Fig. 3 is a plan view of the key-base and its posts.

15 The leading feature of my design consists of the design of the sounder-base, the anvil-base, and the key-base, with their posts or uprights, the same being as relates to the said bases diamond shape in their boundary outline, and 20 as relates to the posts or uprights diamond shape in cross-section.

In the accompanying drawings, embracing 25 my design, A is the sounder-base. B is the anvil-base, and C is the key-base, the boundary outline of which is of a diamond shape, while

the uprights or posts D of the anvil-base, the posts or uprights a a of the sounder-base, and the posts or uprights d d of the key-base are of a diamond shape in their cross-section.

Having thus fully described my newly-discovered design, what I claim, and desire to secure by Letters Patent, is—

1. In a design for a frame for a telegraph-instrument, the design for the sounder-base, the anvil-base, and the key-base thereof, the 35 boundary outline of which is of diamond shape, each being provided with a post or upright.

2. In a design for a frame for a telegraph-instrument, the design for the sounder-base, 40 the anvil-base, and the key-base thereof, the boundary outline of which is of diamond shape, each being provided with a post or upright which is of diamond shape in cross-section.

MURRAY BACON.
